AMPLIFIER TUBE FOR HIGH FREQUENCIES

Gerhard Liebmann, Cambridge, England, assignor to Cathodeon Limited, Cambridge, England, a British company

Application July 29, 1946, Serial No. 687,022
In Great Britain November 20, 1941

12 Claims. (Cl. 250—27.5)

1

The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

A construction of this type of tube has been used in which the cathode, the grid and the anode form substantially plane surfaces perpendicular to the axis of the tube and parallel to each other. Although tubes made according to this design are operating successfully, they are very difficult to construct. The main reason for the difficulty seems to be that it is not easy to adjust the distances between the electrodes with the required accuracy, that the grid and cathode are liable to mechanical distortion which produces changes in the tube characteristics, and that thermal expansion of the electrodes in operation changes the tube parameters.

These disadvantages are avoided to a considerable extent in a tube constructed according to the present invention. At the same time, the proposed improved construction lends itself easily to the methods of mass production.

An amplifier tube according to the invention has concentric electrodes of circular, elliptical, rhomboidal or other suitable cross-section disposed coaxially in the tube envelope and comprising a cathode next surrounded by a grid electrode which is in turn surrounded by a plate electrode or anode, said grid electrode next to the cathode having electrostatic shields conductively secured thereto which are disposed so as to shield the anode and its lead-in wire from the cathode and its lead-in wire.

In constructing a tube embodying the invention, the said grid electrode next to the cathode, which serves as the control grid of the tube when in operation, is mounted on and conductively secured to a metallic grid shield which screens the input and output circuit elements from each other, and may be continued outside the tube envelope.

10 The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

15 A construction of this type of tube has been used in which the cathode, the grid and the anode form substantially plane surfaces perpendicular to the axis of the tube and parallel to each other. Although tubes made according to this design are operating successfully, they are very difficult to construct. The main reason for the difficulty seems to be that it is not easy to adjust the distances between the electrodes with the required accuracy, that the grid and cathode are liable to mechanical distortion which produces changes in the tube characteristics, and that thermal expansion of the electrodes in operation changes the tube parameters.

20 These disadvantages are avoided to a considerable extent in a tube constructed according to the present invention. At the same time, the proposed improved construction lends itself easily to the methods of mass production.

25 An amplifier tube according to the invention has concentric electrodes of circular, elliptical, rhomboidal or other suitable cross-section disposed coaxially in the tube envelope and comprising a cathode next surrounded by a grid electrode which is in turn surrounded by a plate electrode or anode, said grid electrode next to the cathode having electrostatic shields conductively secured thereto which are disposed so as to shield the anode and its lead-in wire from the cathode and its lead-in wire.

30 The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

35 A construction of this type of tube has been used in which the cathode, the grid and the anode form substantially plane surfaces perpendicular to the axis of the tube and parallel to each other. Although tubes made according to this design are operating successfully, they are very difficult to construct. The main reason for the difficulty seems to be that it is not easy to adjust the distances between the electrodes with the required accuracy, that the grid and cathode are liable to mechanical distortion which produces changes in the tube characteristics, and that thermal expansion of the electrodes in operation changes the tube parameters.

40 The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

45 The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

50 The invention refers to improvements in certain types of amplifier tubes for high frequencies in which the output load is connected between the control electrode or grid of the tube and the anode, and the high frequency modulation is applied to the cathode. Such tubes, sometimes called "grounded grid triodes" require a higher input driving power owing to increased input loading and have a lower gain than ordinary tubes of similar construction, but they are more stable in operation if proper screening is provided and possess a lower noise lever, probably due to the absence or reduction of induced noise.

expansion under the action of heat is only very slight. As all the electrodes are kept in proper alignment by the mica spacers and a symmetrical arrangement is used, the alignment can be achieved and maintained with great accuracy and the assembling of the complete electrode structure can be entirely separated from the sealing-in process. Another advantage of the use of tubular electrodes is their greater mechanical strength. The ratio of length of electrode structure to its diameter depends on the use to which this type of tube is put. In many cases, particularly at very high frequencies, the ratio will be rather small, say of the order of one, giving a rather squat structure. Usually, however, this ratio will be nearer to the values common in the art.

In some cases the mica end plates are kept in proper relation to each other by securing them by means of rivets or eyelets or lugs to the anode or to supporting wires fixed to the anode. In this case the metallic grid shield has to be provided with depressions at the points where the anode support wires pass through the mica bottom plate in order to avoid electrical contact and to decrease the stray capacity between grid and anode. In other cases the control grid may have to support the top mica plate and the anode may be kept in its proper position at the lower end by an additional mica spacer.

The invention is more particularly concerned with triodes, but if a very high amplification factor is required, an additional screen grid can be placed between control grid and anode. This grid can be connected to the control grid or a suitable direct current voltage may be applied to it. It is, of course, grounded for high frequency. If this auxiliary grid is kept at a positive potential with respect to cathode potential, the usual means for keeping the auxiliary grid current very low to avoid the introduction of partition noise are employed.

In order that the invention may be more clearly understood, various embodiments thereof will now be described, by way of example, with reference to the accompanying drawings in which—

Fig. 1 shows a sectional view of one construction of tube embodying the invention.

Fig. 2 shows a modified construction in which the electrodes are carried on a moulded glass base.

Fig. 3 shows diagrammatically a plan view of the structure shown in Fig. 2.

Fig. 4 shows a modified construction of tube for working with resonant line circuits.

Referring to Fig. 1, this shows a grounded grid triode in which a copper annulus 2, sealed through the glass envelope 1, divides the input and output circuits. The concentric electrode assembly is mounted on a metal screen 3, which is larger than the hole in the copper disc 2, through which the electrode assembly is passed when the tube is being assembled. The metal screen 3 directly carries the grid supporting wires 4, and through the medium of the mica discs 5 and 6 supports the cathode 7 and anode 8. The screen 3 is provided with a stepped form as shown in order that the anode supporting wires passing through the lower mica disc 5 shall not touch the metal screen. The top of the grid is closed by a screening cap 9 and the anode lead passes to the cap 10 on the top of the tube envelope 1.

In order to be able to assemble the tube, the hole in the copper disc is made larger than the electrode assembly so that when the electrode as-

sembly has been mounted on the glass stem 11, the whole is inserted into the tube envelope. The screen 3 is conductively secured to the copper disc 2 by means of fixing lugs 12 depending from the disc 2 which pass through apertures or slots in the screen 3 and are twisted or bent over. Thereafter the stem 11 is sealed into the glass envelope 1 in the usual way and the tube base fitted.

A certain difficulty is sometimes encountered in the production of tubes according to the improved construction. This difficulty arises from the fact that it is not easy to shape the anode located rather near the disc shaped screen between input and output circuits in such a way that it can be degassed by high frequency eddy currents without glowing unduly, and thus distorting the screen. This difficulty can be overcome by selecting suitable materials for the anode and for the disc. An improvement is brought about by making the disc from copper, only some inset to which the grid proper is fastened, and the anode itself being made from nickel. A further improvement is achieved by using iron as the anode material, the screen being made entirely from nickel or copper. The combination of copper screen and iron anode is the best one but is mostly not required. The iron anode may be made from a non-rusting iron alloy of high permeability, or the iron anode may be nickel plated to prevent it from rusting during the production process.

Figures 2 and 3 show a modified construction in which the electrode structure is supported by a moulded glass base 14 having sealed-through lead-in pins. The electrode assembly is similar to that shown in Fig. 1 and is similarly mounted on the disc-shaped grid shield 3a secured to the grid 4. In this embodiment, however, the electrode leads are all taken through the moulded glass base 14, and the shield 3a is bent to form a depending flange portion 3b which extends between the anode lead-in pin 13 and the rest of the leads. In some cases it is found advantageous to employ a double lead for the anode in order to reduce lead inductance, to which end the anode may be connected to two such lead-in pins as 13 which, as will be understood, are disposed at the same side of the flange 3b. The shield 3a is conductively secured by its flange 3b to one or more (conveniently two) of the lead-in pins, as indicated at 15; whereby the electrode assembly mounted on the shield is supported. All the lead-in pins, namely, pin 16 for the cathode, pins 17, 18 for the cathode heater, pin or pins 15 for the grid with its shield, and pin or pins 13 for the anode, may be arranged in a circle near the periphery of the moulded glass base 14. Alternatively, the cathode and its heater may be connected to lead-in pins grouped together within and near the centre of a circular arrangement of lead-in pins to which the other electrodes are connected. The screening provided by the shield 3a may be continued outside the tube envelope by external screens, if desired.

Instead of taking the anode lead through the moulded glass base 14, the anode lead may be taken through the top end of the tube envelope, as in the embodiment of Fig. 1. In this case, the disc-shaped grid shield 3a would not need to be bent to form the flange portion 3b as previously described, but may, however, be associated, or combined in an integral structure, with a tubular screening member which surrounds the input leads, or the electrode assembly, or both. Thus,

the disc 3a may, for example, be formed with a depending tubular flange or skirt, or be conductively secured to a further tubular screen member forming such a skirt, which surrounds the input leads. Such tubular screen member may be a cylinder which also extends upwardly above the disc 3a so as also to surround the electrode assembly, the disc 3a thus forming a partition across the cylinder. The anode lead taken through the top of the tube envelope may be 10 brought out as a single wire, or as a double wire to reduce lead inductance. Alternatively, in a construction intended to work with resonant line circuits, the lead-in wire or wires for the anode may be replaced by a metal tube sealed through the glass wall of the envelope or to the glass in a manner known per se or as described in British Patent No. 553,350, this tube being closed at its lower end or at another point by a diaphragm and being connected to the anode by means of a spring clip formed by tongues fixed to the top end of the anode. This metal tube may be sealed to the envelope before being pushed into the anode clip. Further, an exhaust tube may be provided which is sealed to the anode lead-in tube and is covered, after exhaust and sealing-off, by an external extension of the tube, as described in the above-mentioned patent.

Fig. 4 shows a modified construction for working with concentric line resonators. A copper annulus 21 is sealed through the wall of the tube envelope 20 and separates the input and output circuits of the tube. Also sealed through the wall of the envelope are two annular flanged copper members 22 and 23 arranged as shown. The upper member 22 carries the anode 24 (and may be made integral therewith) and the lower member 23 carries the cathode 25. The grid 26 is carried by the screen 27 which is secured to the copper annulus 21 by eyelets or twisted lugs 28. The upper end of the grid is closed by the screening cap 29 and the electrodes are spaced by mica washers 30 in well-known manner. The aperture in the centre of the member 23 is made sufficiently large to allow the screen 27 to pass therethrough during assembly.

The inner conductors of the concentric line circuits are constituted by metal cylinders 31, 32 which are a push fit on or inside the flanges of the members 22, 23 respectively. The outer conductors of the lines are also constituted by metal cylinders 33 and 34 which are insulatingly supported on opposite sides of the grounded copper screen 21. The tuning of the resonant lines is effected by annular plungers 35, 36 sliding within the pairs of tubes 31, 33 and 32, 34, respectively.

I claim:

1. An amplifier tube having an envelope, concentric electrodes disposed coaxially in said envelope, said electrodes including a cathode next surrounded by a grid electrode and an anode surrounding said grid electrode, said grid electrode next to said cathode being conductively mounted by one end thereof on a metal screening annulus sealed through the wall of said envelope substantially perpendicularly to the axis of said envelope, the other end of said grid electrode being closed by a metal screening cap conductively secured thereto, a flanged metal member sealed through said envelope wall substantially parallel to said screening annulus and electrically connected to said cathode, with the flange of said member disposed outside said envelope.

2. An amplifier tube as defined in claim 1, 75

wherein said flanged metal member supports said cathode.

3. An amplifier tube as defined in claim 1, and further comprising a metallic tube fitting said flange of said flanged metallic member, and constituting an internal conductor of a concentric resonant line.

4. An amplifier tube as defined in claim 1, and further comprising a metallic tube fitting said flange of said flanged metallic member and constituting the internal conductor of a concentric resonant line, and a metal cylinder surrounding said metallic tube and constituting the external conductor of said resonant line, an end of said outer metal cylinder lying adjacent to but insulated from said metal screening annulus.

5. An amplifier tube having an envelope, concentric electrodes disposed coaxially in said envelope, said electrodes including a cathode next surrounded by a grid electrode and an anode surrounding said grid electrode, said grid electrode next to said cathode being conductively mounted by one end thereof on a metal screening annulus sealed through the wall of said envelope substantially perpendicularly to the axis of said envelope, the other end of said grid electrode being closed by a metal screening cap conductively secured thereto, a flanged metal member sealed through said envelope wall substantially parallel to said screening annulus and electrically connected to said anode, with the flange of said member disposed outside said envelope.

6. An amplifier tube as defined in claim 5, wherein said flanged metal member supports said anode.

7. An amplifier tube as defined in claim 9, and further comprising a metallic tube fitting said flange of said flanged metallic member, and constituting an internal conductor of a concentric resonant line.

8. An amplifier tube as defined in claim 5, and further comprising a metallic tube fitting said flange of said flanged metallic member and constituting the internal conductor of a concentric resonant line, and a metal cylinder surrounding said metallic tube and constituting the external conductor of said resonant line, an end of said outer metal cylinder lying adjacent to but insulated from said metal screening annulus.

9. An amplifier tube having an envelope, concentric electrodes disposed coaxially in said envelope, said electrodes including a cathode next surrounded by a grid electrode and an anode surrounding said grid electrode, said grid electrode next to said cathode being conductively mounted by one end thereof on a metal screening annulus sealed through the wall of said envelope substantially perpendicularly to the axis of said envelope, the other end of said grid electrode being closed by a metal screening cap conductively secured thereto, two flanged metal members sealed through said envelope wall substantially parallel to said screening annulus and at opposite sides thereof, one of said members being electrically connected to said cathode and the other of said members being electrically connected to said anode, the flanges of both said members being disposed outside said envelope.

10. An amplifier tube as defined in claim 9, wherein said flanged metal members respectively support the electrodes to which they are connected.

11. An amplifier tube as defined in claim 9, and further comprising two aligned metallic tubes at opposite sides of said screening annulus, which

respectively fit said flanges of said flanged metallic members and which constitute internal conductors of concentric resonant lines coupled respectively with the input and output circuits of the amplifier tube.

12. An amplifier tube as defined in claim 9, and further comprising two aligned metallic tubes at opposite sides of said screening annulus, which respectively fit said flanges of said flanged metallic members and which constitute internal conductors of concentric resonant lines associated respectively with the input and output circuits of the amplifier tube, and two aligned metal cylinders surrounding said metallic tubes respectively and constituting the external conductors of said lines, the adjacent ends of said outer metal cylinders lying adjacent to but insulated from said screening annulus. 15
